UNITED STATES PATENT OFFICE

151,129

DESIGN FOR A HAT

G. Howard Hodge, New York, N. Y.

Application June 17, 1947, Serial No. 139,762

Term of patent 3½ years

(Cl. D3—13)

To all whom it may concern:

Be it known that I, G. Howard Hodge, a citizen of the United States of America, residing in New York, county of New York, and State of New York, have invented a new, original, and ornamental Design for a Hat, of which the following is a specification, reference being had to the accompanying drawing, forming part thereof.

Fig. 1 is a front perspective view of a hat, showing my new design.

Fig. 2 is a rear perspective view thereof.

I claim:

The ornamental design for a hat, substantially as shown.

G. HOWARD HODGE.
